UNITED STATES PATENT OFFICE.

HEINRICH KOPPERS, OF ESSEN-ON-THE-RUHR, GERMANY, ASSIGNOR TO H. KOPPERS COMPANY, OF CHICAGO, ILLINOIS, A CORPORATION.

COOLING APPARATUS.

1,099,255.

Specification of Letters Patent.

Patented June 9, 1914.

Application filed July 8, 1913. Serial No. 777,829.

To all whom it may concern:

Be it known that I, HEINRICH KOPPERS, engineer, residing at Moltkestrasse 29, Essen-on-the-Ruhr, in Prussia, Germany, have invented certain new and useful Improvements in Cooling Apparatus, of which the following is a specification.

In connection with coolers comprising outer tubes surrounding an inner tube or tubes, it has been proposed to connect one 10 end or both ends of the inner tubes to the casing of the cooler by means of stuffing-boxes in such a manner as to allow of movement of the tubes under expansion. The 15 stuffing-boxes heretofore employed have the disadvantage that in course of time, wear or deterioration of the packing material enables the cooling liquid on one side, which is generally under higher pressure, to leak into 20 the material which is to be cooled. It is also difficult to determine when there is a leak with the result that the liquid in process of 25 cooling is spoiled. Thus, for instance, in the cooling of benzol washing oil leakage will produce an emulsion which renders the oil unfit for further use. These disadvantages are obviated by the present invention, according to which a ring is placed between 30 the pliable packing rings so as to divide the stuffing-box packing into two parts, one of which makes a tight joint against the material to be cooled, and the other makes a tight joint against the cooling liquid, the 35 said intermediate ring having radial holes or ducts which allow any liquid which may have leaked past one packing to escape outward. This arrangement enables the cooler to be readily tested for leakage and excludes all possibility of the cooling water reaching 40 the substance to be cooled, since liquid escaping from one part of the stuffing-box is owing to its complete loss of pressure, unable to leak through the other part.

One form of construction of the device is 45 shown in the accompanying drawings, in which:

Figure 1 is an elevation of a cooler, partly in section; Figs. 2 and 3 comprise two views of opposite ends of the apparatus; Figs. 4 50 and 5 comprise two detail views, drawn to a larger scale.

The outer tubes *f* are expanded in the walls of chambered casings *a* and *b*, of which casing *a* is provided with holes *c* and

d for the admission and outlet of the cooling water, while both casings are furnished with baffle walls or partitions *g* which cause the cooling water to take a sinuous path. The inner tubes *h* are expanded at both ends in tube plates *i* and *k*, the plate *i* being 55 pressed against the casing *a* by the caps *l*. The tube plates *k* have a sliding fit in bores in the casing *b*, and dished cover plates *m* establish communication between adjacent sets or groups of inner tubes. This arrangement provides a sinuous path for the liquid to be cooled circulating through the inner tubes, and enables the two liquids to be caused to circulate in the same or in opposite directions.

Interposed between the casing *b* and the covers *m* is a packing device comprising two packing rings *n* and *o* with an intermediate metal ring *p*. The latter is provided with radial bores *q* which communicate with the dividing space between the casing *b* and the cover *m*. It will be seen that the inner tubes are still able to expand freely toward the outer casing without setting up stresses and while avoiding the drawbacks hereinbefore mentioned. Any liquid leaking out between the tube plate *k* and packings *n* and *o* will escape outward through the bores *q* in the ring *p*, and thereby immediately indicate leakage. Hence, after a cooler has 75 been cleaned out (this being frequently necessary) any escape of oil and water will denote leakage at one of the joints. In any case, there is no possibility of leakage past the stuffing-box from one side to the other. 80 It will of course suffice to provide the described joint at one end of the tubes only, although it may be arranged at both ends if desirable.

I claim—

A cooler comprising a pair of chambered apertured casings, an outer tube connecting said casings and expanded in the inner walls thereof, a first apertured cap secured to the outer wall of one of said casings, a first tube plate firmly clamped between said first cap and outer casing-wall, a second apertured cap secured to the outer wall of the other casing and spaced therefrom, a second tube plate slidably mounted in the apertures of 95 said second cap and last named outer casing wall, inner tubes loosely inclosed by the outer tube and expanded in both of said

tube plates, an interiorly grooved ring fitted on the second tube plate intermediate the second cap and the opposed outer casing-wall, said ring being provided with radial 5 bores that connect the groove with the atmosphere, and a packing ring located on each side of the interiorly grooved ring.

In witness whereof I have signed my name to this specification in the presence of two subscribing witnesses.

HEINRICH KOPPERS.
